DESK STAND FOR A COMBINATION TELEPHONE STATION AND SWITCHING UNIT

Donald John Booty, Chicago, Ill., assignor to International Telephone and Telegraph Corporation

Filed Jan. 9, 1961, Ser. No. 63,491

Term of patent 14 years

(Cl. D26—14)

FIG. 1

FIG. 2

FIG. 1 is a perspective view of a desk stand for a combination telephone station and switching unit, showing my new design; and

FIG. 2 is a rear elevation of the desk stand.

I claim:

The ornamental design for a desk stand for a combination telephone station and switching unit, as shown.
